UNITED STATES PATENT OFFICE.

RODNEY G. RICHARDSON, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed February 4, 1918, Serial No. 215,236. Renewed April 12, 1923.

To all whom it may concern:

Be it known that I, RODNEY G. RICHARDSON, a citizen of the United States of America, and resident of Chicago, Cook County, 5 State of Illinois, have invented certain new and useful Improvements in Automatic Telephone Systems, of which the following is a specification.

My invention relates in general to improvements in systems in which the connections are extended by the use of a calling device by a subscriber and without the intervention of an operator at the main or central exchange.

More specifically my invention provides improved switching apparatus and circuits for use in a system of the above character.

Among other objects of my invention is the provision of a more simple and efficient 20 method of operating automatic switches of the type known as two-wire. Other features and the manner of operation will be pointed out hereinafter. In the drawings, Figs. 1 and 2 illustrate an established connection 25 between a calling and a called subscriber in a system which employs switches embodying my invention.

Figure 1 shows a substation A of well known type comprising a transmitter 2, 30 receiver 3, calling device CD, having the usual impulse springs 4 and 5, ringer 6, condenser 7, and the switch hook 8 controlling the springs 9, 10 and 11.

Associated with the line conductors 12 35 and 13 of the substation A and individual thereto is the line switch C of the well known rotary type similar to that shown in United States Letters Patent No. 1,126,727 to Dietl which embodies certain features of my invention and comprises a line relay 14, a 40 switching relay 15, and a rotary magnet 16. The rotary magnet 16 operates to rotate the wipers 17, 18 and 19 over a number of contacts to which are connected the line and 45 test conductors which lead to a number of so called selector switches, similar to that shown at D, which are of a similar type and construction to the selector switch shown in U. S. Letters Patent No. 815,321, granted 50 March 13, 1906, to Keith, Erickson and Erickson, except that the circuits are modified to adapt it for the well known two-wire control. The said selector D differs also

from the selector shown in said patent in certain features relating to my improved 55 method of operation as will be pointed out. The selector D comprises mainly a line relay 20, switching relay 21, slow release relay 22, slow series relay 23, vertical magnet 24, rotary magnet 25, and release magnet 60 26. The wipers 27, 28, and 29 are controlled through the medium of line relay 20 and the vertical and rotary magnets 24 and 25 to test and connect with any one of a plurality of contacts each set of which is connected to the line and test conductors of a connector switch similar to that shown at E (Fig. 2).

The connector switch E is of a well known type similar to that shown and described 70 in U. S. Letters Patent No. 815,176, granted March 13, 1906, to Keith, Erickson and Erickson except that the circuits have been modified to adapt it to the well known two-wire method of control. The connector E 75 comprises among other details, the line relay 30, release relay 31, series relay 32, busy relay 33, back bridge relay 34, ring cut-off relay 35, wiper cut on relay 36, vertical magnet 37, rotary magnet 38, private magnet 39, 80 and release magnet 40. The usual busy machine is shown at M and the ringing generator at R, controlled by an interrupter relay 41. This connector E is operated in response to impulses from the substation A 85 to raise the wipers 69, 70 and 71 to a desired level and then rotate them to a set of contacts which lead to a desired subscriber's line. The substation A' and its associated switch C' are similar in all respects to the 90 substation A and the switch C (Fig. 1).

I will now trace in detail the circuits and method of operation when the subscriber A desires to establish a talking connection with another subscriber (A' for instance).

Upon the removal of the receiver at the substation A, a circuit is closed at the springs 9 and 10 for the line relay 14 of the individual switch C, to perform a preliminary trunking operation. It will be understood that a switch of this character always stands with its wipers in connection with the trunk line last used by the calling subscriber, which trunk may now be either idle or busy. The line relay 14 energizes over a circuit including the line conductors 12 and 13 and

the substation A and operates to close a circuit for the switching relay 15 from ground G' through springs 42, and the upper winding of relay 15. At the same time a circuit 5 is closed from the private wiper 19 through the springs 43 and 44, and springs 45, from whence the circuit divides, one branch passing through the lower winding of the relay 15 to battery and the other passing through 10 the interrupter springs of the rotary magnet 16 and through said magnet 16 to battery. The relay 15 is differentially wound, that is when current passes through both of 15 its windings, the armatures will not be attracted, due to the windings being wound in opposite directions. Therefore if the trunk upon whose test conductor the wiper 19 is resting, is busy, a ground will be found thereat and the relay 15 will therefore remain in its normal position. The ground 20 from the private wiper will however cause the operation of the rotary magnet 16 over the circuit traced, and said magnet will operate as a buzzer to rotate the wipers 17, 18 25 and 19 to the next set of contacts, which is in turn tested by the private wiper. If this next set of contacts is busy, the same cycle of operations will occur and the rotary magnet will therefore continue to rotate the 30 wipers until an idle trunk line is reached.

When an idle trunk line is reached there will be no ground on the contact which the private wiper 19 engages and therefore no circuit will be closed for the rotary magnet 35 16 or for the lower winding of the relay 15. The relay 15 will therefore attract its armatures, due to the fact that the current flowing in the upper winding is not opposed, to disconnect the line relay 14 and ground 40 G² from the line conductors 12 and 13 and to extend said line conductors to the wipers 17 and 18, at the springs 45 and 46. The relay 15 also closes a locking circuit for 45 itself which extends from the wiper 19 through springs 43 and 47 to its upper winding. The relay 14 being slow acting maintains the circuit for the upper winding of relay 15 closed at springs 42 until the selector D has time to operate and supply 50 ground to the holding circuit above traced.

As soon as the switching relay 15 extends the line conductors to the wipers 17 and 18 and therefore to the conductors leading to the selector D, a circuit is established for the line relay 20 of said selector which extends 55 from ground through the lower winding of said relay, springs 48 and 49, wiper 18, to and through the substation A and back to the wiper 17, springs 50 and 51, and through 60 the upper winding of relay 20 to battery. Relay 20 energizes over this circuit and operates to close a circuit from ground through the springs 52 and 53 and through the relay 22 to battery. The relay 22 energizes 65 to supply ground to the holding circuit of

the relay 15 of line switch C at springs 54 and also prepares a circuit for the switching relay 21 and the rotary magnet 25 at the same springs. This circuit may be traced from ground through springs 54, 70 springs 55, to a point 56, where the circuit divides, one branch extending through the lower winding of relay 21 and another through the rotary off-normal springs 57 and the upper winding of said relay, where 75 the two branches meet and extend to the normally open spring contact 58. Another branch of the above circuit extends from the point 56, through the springs 57 and the rotary magnet 25 and its interrupter springs 80 to the same spring 58. The operation of relay 22 also prepares a circuit for the vertical magnet 24 and series relay 23 at springs 59 and 60 and opens one point in the circuit of the release magnet 26 at springs 85 59 and 61.

The subscriber now operates his calling device CD to separate the springs 4 and 5 a number of times corresponding to the first digit of the called subscriber's number. The 90 separation of the springs 4 and 5 causes the line relay 20 to be deenergized a corresponding number of times to thereby close and open the circuit of the vertical magnet 24 and slow relay 23 a corresponding number 95 of times. It will be understood that the relay 22, being slow acting, maintains its armature attracted during impulses in spite of its circuit being opened at springs 52 and 53. The circuit of the vertical magnet extends 100 from ground through springs 52 and 62, springs 63, springs 59 and 60, and through relay 23 and vertical magnet 24 to battery. The vertical magnet 24 operates in response to these impulses to raise the wipers 27, 28 105 and 29 to a desired level of the contacts which lead to connector switches E which have access to the desired group of lines. As soon as the switch D takes its first vertical step, the spring 64 is allowed to make contact with the springs 58 and 65. The closure of springs 64 and 65 closes at one point the circuit of release magnet 26, which circuit is maintained open at the springs 59 110 and 61 of relay 22. The closure of springs 64 and 58 closes another point in the circuit of the rotary magnet 25 and also of relay 21. The slow relay 23 energizes in series 115 with the vertical magnet, remains in energized position throughout the sending of the impulses for the first digit and therefore maintains the two last mentioned circuits of relay 21 and magnet 25 open at springs 55. 120

As soon as the impulses for this first digit cease, the line relay 20 comes to rest 125 energized, thereby maintaining the relay 22 energized and opening the circuit of relay 23 for a length of time sufficient to cause the deenergization thereof. Relay 23, upon deenergizing, again closes the springs 55 to 130

cause an initial operation of the rotary magnet 25 over a circuit from ground through springs 54, springs 55, springs 57, rotary magnet 25 and its interrupter springs, and 5 through springs 58 and 64 to battery. The magnet 25 thereupon operates to rotate the wipers 27, 28 and 29 onto the first set of contacts leading to connector (similar to E). It will be noticed that a circuit for the two 10 windings of relay 21 in multiple was also closed at this time by springs 55. The relay 21, however, is constructed in the same manner as the relay 15 of line switch C and therefore does not attract its armatures 15 at this time; as soon as the wipers take their first rotary step, however, the rotary off-normal springs 57 are opened, thereby breaking the initial operating circuit of the rotary magnet and also the circuit of the 20 upper winding of relay 21.

Further operation of the selector now depends upon the busy or idle condition of the various test contacts of the trunk lines over which the wiper 29 passes. If the associated 25 trunk line is busy the wiper 29 will find a ground potential present at said contact from an occupying switch (not shown) while such potential will be absent if the line is idle.

Assuming the first trunk line of the level 30 to be busy, then as soon as wiper 29 meets said contact a new circuit will be closed for the rotary magnet and for the upper winding of relay 21. Relay 21 will therefore 35 have no chance to attract its armature. The circuit extends from ground at wiper 29, springs 66 and 67, and through the rotary magnet 25 and upper winding of relay 21 in multiple to battery through springs 58 40 and 64. The magnet 25 will therefore operate in the manner of a buzzer to advance the wipers 27, 28 and 29 to an idle trunk line. When such idle trunk line is reached, it will be clear that no circuit is closed for 45 the rotary magnet or for the upper winding of relay 21. The relay 21 will therefore energize through the medium of its lower winding to switch the incoming line conductors over to the wipers 27 and 28 and 50 disconnect the line relay 20 therefrom. The relay 21, upon energizing, opens the circuit of the rotary magnet at springs 66 and 67 to prevent further rotation and close a locking circuit for itself from the private wiper 55 29 through springs 66 and 68 and through its lower winding to battery, and also opens another point in the release circuit at springs 63. The relay 22 maintains the circuit for the lower winding of relay 21 60 closed for a short interval after its circuit is opened by relay 20 to give the switch ahead time to operate to supply ground to the above traced holding circuit.

As soon as relay 21 energized to switch 65 the line conductors through, a circuit was

closed for the line relay 30 of connector switch E extending from ground through the lower winding of relay 30 to wiper 28, thence to and through the line circuit of substation A and back through the other 70 side of the line and wiper 29, through the upper winding of relay 30 to battery. Relay 30 therefore replaces the relay 20 of the selector D under the control of the calling device CD. Relay 30, upon energizing, 75 closes a circuit for relay 31 which in turn energizes to place a ground on the holding circuit of relay 21 of switch D at its upper springs, opens a point in the circuit of release magnet 40 and prepares a circuit for 80 the series relay 32 and vertical magnet 37. It may be noted that a branch of this holding circuit for the relay 21 also extends through the springs 55 of relay 23 and to the holding circuit of relay 15 of switch C, 85 from which ground is disconnected at springs 54 when relay 22 deenergizes. The switches C and D therefore are held up by the single ground from the springs of relay 31 at the connector. The line relay 30 90 is thereupon controlled in the usual well known manner to first raise the wipers 69, 70 and 71 to a desired level through the medium of the vertical magnet 37 in response to one digit; to then allow the side 95 switch to pass to second position by means of relay 32 and private magnet 39; and to then, in response to the last digit, control the rotary magnet 38 in a similar manner to cause the line and private wipers to connect 100 with the particular set of contacts desired, which in this case lead to the substation A' and its individual switch C'. Assuming the called line to be idle when connection is made therewith, the side switch wipers will 105 immediately pass to third position and relay 36 will be energized to connect the interrupted generator circuit with the called line to signal the called subscriber. Another result of the side switch passing to 110 third position is the closure of a circuit for the upper winding of the switching relay 15' of the line switch C' from ground through side switch wiper 72, (in third position) wiper 71, and through the upper 115 winding of said relay to battery. The mechanical operation of the line and cut-off relays 15' and 14' of the line switches C and C' is similar to that of the line and cut-off relays of the line switch shown in U. S. Letters Patent No. 1,186,471, granted June 6, 1916, to John Erickson, that is, the relay 15' cannot fully attract its armatures 120 unless the relay 14' has first been energized. So that when a call is made to the line of substation A' and a circuit is closed for a winding of relay 15', its armatures will be attracted only far enough to disconnect the line relay 14' and ground from the called line, but not far enough to connect the line 125 130

through to the calling wipers of said switch.

As soon as the called subscriber hears his signal, he removes his receiver from the hook and closes a circuit for the ring-cut-off relay 35 of the connector which locks up and connects the called subscriber's line to the incoming talking circuit through condensers 73 and 74 and also to the back bridge battery supply relay 34. Conversation may then be carried on over the heavy conductors shown in the drawing.

If the called line had been busy when connection was extended thereto, the connector E would have been locked in second position by the ground on the private or test contact and busy tone from the busy machine M would be supplied to the calling man. The ground is extended from private wiper 71, through the side switch wiper 72 (in second position) and through the busy relay 33 and private magnet 39 to battery.

When conversation is completed, the connection may be released by the hanging up of the receiver at the calling substation, thereby opening the circuit of the line relay 30 of the connector switch E (Fig. 2). The relay 30 upon deenergizing, opens the circuit of slow relay 31 at the front contact of its springs and closes a point in the circuit of the release magnet 40 at the back contact of said springs. The relay 31, upon deenergizing, closes the circuit of release magnet 40 to release the switch E and also opens the holding circuit for the switching relays 21 and 15 of selector switch D and line switch C (Fig. 1). Relay 21, upon deenergizing, closes a circuit at springs 63 for the release magnet 26 to release the switch D in the usual manner, and relay 15, upon deenergizing, restores the circuit of the line relay 14 to the control of the substation A in readiness for the next call.

It will thus be seen that I have provided an improved type of line and selector switches in which a differential relay is used in place of the usual switching relay which has been in the past short circuited during the rotation of the line and selector switches, and I have also provided a very simple and highly efficient method of controlling said differential relays to control the operation of a switch.

Having fully described and ascertained the features of my invention, what I consider to be new and desire to have protected by Letters Patent will be pointed out in the appended claims.

What I claim as my invention is:

1. In a telephone system, an automatic switch, a rotary magnet for said switch, a differential relay therefor, a circuit for said rotary magnet controlled by said differential relay, means for closing a circuit for

said differential relay and said rotary magnet to start the operation of said switch, means for substituting a second circuit for said differential relay and said rotary magnet to continue the operation of said switch, 70 said differential relay adapted to remain deenergized during the operation of said switch, and means for energizing said differential relay to open said last mentioned circuit when the operation is completed. 75

2. In a telephone system, trunk lines arranged in groups, an automatic switch controllable over a calling line to select one of said trunk groups and an idle trunk in the selected group, a differentially wound switching relay for extending the calling line to the selected trunk after the switch has operated, circuits for the two windings of said relay one of which serves to prevent the energization of said relay during the trunk selecting movement, and means for closing said circuits when the group selecting operation is completed.

3. In a telephone system, trunk lines arranged in groups, an automatic switch controllable over a calling line to select one of said trunk groups and an idle trunk in the selected group, a differentially wound switching relay for extending the calling line to the selected trunk after the switch has operated, circuits for the two windings of said relay the second of which prevents the said relay from energizing, means for closing said circuits when the group selecting operation is completed, and means for substituting a test circuit for the said second circuit after the trunk selecting movement is started, whereby the said relay is caused to energize when an idle trunk line is selected. 100

4. In a telephone system, a subscriber's individual line or trunk selecting switch, means for operating said switch when a call is made to extend said line to an idle trunk line, a combination cut-off and switching relay in said switch having differential windings, means for energizing one winding of said relay when the line is called, and means for energizing both windings when the line is calling and the switch is operated. 110

5. In a telephone system, a subscriber's individual line or trunk selecting switch, means for operating said switch when a call is made to extend said line to an idle trunk line, a combination cut-off and switching relay in said switch having a holding winding, means for energizing said winding when the line is calling or being called, and another winding differentially connected to prevent said relay from energizing while the switch is operating to select an idle trunk line. 120

6. In a telephone system, a subscriber's individual line or trunk selecting switch, a combination cut-off and switching relay in 130

said switch, a line relay normally connected to the line, means for energizing said combination relay to cut-off said line relay when the line is called, means for energizing said combination relay to extend said line to an idle trunk line when the said line is calling, and a differential winding for said combination relay to prevent the same from energizing while an idle trunk line is being selected.

7. In a telephone system, an automatic switch, trunk lines accessible thereto, line and test wipers for said switch, a magnet for moving said wipers over contacts of said trunk lines, a differential switching relay for connecting said wipers, means for simultaneously closing two opposed circuits for said relay and a circuit for said magnet to start the operation of the switch, means actuated upon the initial movement of the wipers for opening the second circuit of said relay, and another circuit for said relay including said test wiper, said last mentioned circuit being effective after the second circuit is opened to prevent the relay from energizing until an idle trunk line is found.

8. In a telephone system, an automatic switch, line and test wipers for said switch, trunk lines accessible to said wipers, a magnet for moving said wipers over contacts of said trunk lines, a differential switching relay for connecting said wipers, means for closing two opposed circuits for said relay and an initial energizing circuit for said magnet to start the advance of the wipers of said switch to select an idle trunk line, means actuated upon the initial movement of the wipers for opening the magnet circuit and one circuit of said relay, and other circuits completed by way of said test wiper when the last mentioned circuits are opened for continuing the operation of said magnet and for preventing said relay from energizing until an idle trunk line is found.

9. In a telephone system, an automatic switch, a line relay for said switch, a switching relay for disconnecting said line relay, vertical and rotary magnets for said switch controlled by said line and switching relays, means for first operating said line relay to operate said vertical magnet, an auxiliary relay energized during the operation of the vertical magnet and deenergized after said operation to close a circuit for said rotary magnet and two opposed circuits for said switching relay, said switching relay adapted to remain inoperative upon closure of its circuits, and said rotary magnet adapted to operate in response to the closure of its circuit to operate said switch, and means controlled by said rotary magnet for opening one circuit of said switching relay, whereupon said switching relay is energized by means of its other circuit.

10. In a telephone system, a line terminating in an automatic switch, trunk lines accessible to said switch, means for operating said switch to automatically select an idle one of said trunk lines, a differentially wound switching relay for extending said line to the selected trunk line after the switch has operated, an energizing circuit for said relay including one winding thereof, a second circuit including the other winding of said relay for preventing the relay from energizing, off normal contacts for opening the said second circuit at the beginning of the trunk selecting operation, a test wiper for said switch, and a third circuit including said test wiper for shunting the break in said second circuit to prevent said relay from energizing until an idle trunk line is found.

11. In a telephone system, a line terminating in an automatic switch, trunk lines accessible to said switch, means for operating said switch to automatically select an idle one of said trunk lines, a differentially wound switching relay for extending said line to the selected trunk line after the switch has operated, an energizing circuit for said relay including one winding thereof, a second circuit including the other winding of said relay for preventing the relay from energizing, means for opening the said second circuit at the beginning of the trunk selecting operation and for maintaining it open during the continuation thereof, and a test circuit substituted for said second circuit when the same is opened in order to prevent the said relay from energizing while the switch is passing over busy trunk lines.

12. In a trunk hunting switch for automatic telephone systems, incoming and outgoing release trunk conductors normally connected together, the outgoing release trunk conductor terminating in a test wiper of said switch, a differential wiper switching relay having two windings normally connected to said conductors, respectively, means for breaking the connection between said conductors when the hunting movement starts, means for again connecting said conductors effective only when the hunting movement is finished, and means for disconnecting the outgoing release trunk conductor from the associated relay winding when the last mentioned connection is established.

13. In a trunk hunting switch for automatic telephone systems, incoming and outgoing release trunk conductors normally connected together, the outgoing release trunk conductor terminating in a test wiper of said switch, a differential wiper switching relay having two windings normally connected to said conductors, respectively, means for giving said switch a directive

movement preliminary to its hunting movement, means for opening the incoming release conductor during the directive movement, means for breaking the connection between said conductors when the hunting movement starts, means for again connecting said conductors when the hunting movement is finished, and means for disconnect-

ing one release trunk conductor from its associated relay winding when the last mentioned connection is established. 10

Signed by me at San Antonio, Bexar County, Texas, this 26th day of January, 1918.

RODNEY G. RICHARDSON.
